Primary Examiner — Catherine S Posthauer*(74) Attorney, Agent, or Firm* — SANCHELIMA & ASSOCIATES, P.A.; Christian Sanelima; Jesus Sanelima(57) **CLAIM**

The ornamental design for a suspended container cap, as shown and described.

DESCRIPTION

FIG. 1 is an isometric view of a suspended container cap showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof; and,

FIG. 8 is another isometric view thereof, shown in a position of use with an exemplary container.

The broken lines are shown for the purpose of illustrating both parts of the article as well as environmental subject matter of an exemplary container. None of the broken lines form part of the claimed design.
